UNITED STATES PATENT OFFICE

160,933

MACHINE FOR GENERATING SPHERICAL SURFACES ON ARTICLES

William D. Fowler, Geneva, N. Y., assignor to Shuron Optical Company, Inc., Geneva, N. Y., a corporation of New York

Application February 26, 1949, Serial No. 1,099

Term of patent 14 years

(Cl. D37—1)

To all whom it may concern:

Be it known that I, William D. Fowler, a citizen of the United States of America and resident of the city of Geneva, in the county of Ontario and State of New York, have invented a new, original, and ornamental Design for a Machine for Generating Spherical Surfaces on Articles, of which the following is a specification, reference being had to the accompanying drawings, forming part thereof.

In the drawings:

I claim:

The ornamental design for a machine for generating spherical surfaces on articles, substantially as shown.

WILLIAM D. FOWLER.
